UNITED STATES PATENT OFFICE.

ALONZO C. MATHER, OF CHICAGO, ILLINOIS.

DRAFT-RIGGING.

SPECIFICATION forming part of Letters Patent No. 767,523, dated August 16, 1904.

Application filed December 11, 1903. Serial No. 184,725. (No model.)

To all whom it may concern:

Be it known that I, ALONZO C. MATHER, a citizen of the United States, residing at Chicago, in the county of Cook and State of Illinois, have invented certain new and useful Improvements in Draft-Rigging, of which the following is a specification.

My invention relates to improvements in draft-rigging for cars, and particularly where tandem springs are used.

The object of my invention is to provide a stop or stops against which the draft-bar strikes before the springs reach their limit of contraction, thus avoiding the breaking of the springs by relieving them of the severe strains to which they are frequently subjected.

A further object of my invention is to construct the housing in sections instead of in one piece, as heretofore, so that the parts may be more readily assembled and the cost of manufacturing lessened.

A still further object of my invention is to construct the parts in such a manner that the draft-bar may be readily dropped below the housing for the purpose of inserting or removing the parts.

Referring to the drawings, Figure 1 is a plan view of the draft-rigging. Fig. 2 is a sectional view as on line 2 2, Fig. 1. Figs. 3, 4, and 5 are perspective views of the sectional housing.

A and A' represent the longitudinal timbers which form part of the car. On the inner face of said timbers are bolted the housings, consisting of the end sections B and B' and the intermediate sections C. The sections of the housing on the timber A' correspond to those on the timber A.

The draft-bar D is provided with a yoke D', which is supported between the housings by cross-bars E, which are bolted to the under side of the timbers A and A', as shown in Fig. 2. The yoke is provided with lugs D², formed on the inner side of said yoke. A tie-bolt D³ is passed through the said lugs to prevent the yoke from spreading.

Follower-plates F, F', F², and F³ are placed within the yoke D' and engage projections formed on the housings. Springs G and G' are inserted between the follower-plates F and

F' and tend to hold them against the end sections B of the housings and the projections c on the intermediate sections C, respectively. The springs g and g' tend to hold the follower-plates F² and F³ against the said projections c and the end sections B' of the housings, respectively.

Upon the intermediate sections C of the housings are formed stops C' and C², which limit the travel of the follower-plates.

When the draft-bar is moved in the direction of the arrow, the follower-plates F and F² will remain in a fixed position, but the plates F' and F³ will move with the draft-bar, the plate F' being acted on by the lugs D² on the yoke and the plate F³ by the end d of the yoke. The parts are moved against the action of the springs; but the plates F' and F³ will contact with the stops C' and C², respectively, before the limit of compression of the springs is reached. When the draft-bar is moved in the opposite direction, the plates F' and F³ remain stationary and plates F and F² follow with the draft-bar until the stops C' and C² are reached.

The parts forming one of the housings are shown in Figs. 3, 4, and 5. By constructing the housings in this manner the parts can readily be assembled or removed in case any should break or get out of order.

To remove any of the parts, the cross-bars E are removed, which will allow the draft-bar to drop so that access may be had to any of the parts.

Having thus described my invention, I claim and desire to secure by Letters Patent—

1. In a draft-rigging having a draft-bar and follower-plates carried thereby, the combination of housings consisting of an intermediate section, and end sections located at either end of said intermediate section, said intermediate section having lugs forming part thereof and projecting therefrom to engage said follower-plates, and said end sections and said intermediate section contacting with each other to resist an end thrust, substantially as described.

2. In a draft-rigging the combination of a draft-bar, a yoke having integral lugs projecting toward the center of said yoke, fol-

lower-plates F' and F² on either side of said lugs, follower-plates F and F³, springs acting between the follower-plates F and F', and between follower-plates F² and F³, housings consisting of end sections and an intermediate section secured to timbers A and A', lugs forming part of said intermediate section adapted to engage said follower-plates, the end sections and said intermediate sections contacting with

each other to resist an end thrust, substantially as described.

In testimony whereof I affix my signature in presence of two witnesses.

ALONZO C. MATHER.
